UNITED STATES PATENT OFFICE.

EDWIN T. GREENFIELD, OF NEW YORK, N. Y.

TOOL FOR BUSHING ENDS OF METALLIC TUBES.

SPECIFICATION forming part of Letters Patent No. 640,759, dated January 9, 1900.

Application filed August 30, 1899. Serial No. 728,956. (No model.)

To all whom it may concern:

Be it known that I, EDWIN T. GREENFIELD, a citizen of the United States, residing at New York, borough of Manhattan, county and 5 State of New York, have made a new and useful Invention in Tools for Bushing the Ends of Metallic Tubes, of which the following is a specification.

My invention relates particularly to improvements in tools for bushing or lining the ends of metallic conduits—such, for instance, as is disclosed in United States Patent No. 630,501, granted to me on the 8th day of August, 1899; and its object is to provide a tool 15 which will quickly and permanently affix to the inner ends of such tubular conduits a smooth metallic bushing which when in place will prevent any damaging effect from jagged ends to insulated wires when drawn 20 therein, as is often the case when the ends of such tubes are sawed and the burred or jagged parts left exposed.

In a prior application bearing Serial No. 724,060, filed on the 17th day of July, 1899, I 25 have described, shown, and claimed a metallic tube provided with protecting-bushings at its ends, and no claim is herein made to any such feature, the subject-matter hereof being directed solely to the tool for securing such 30 bushings in place, as hereinafter described, but more specifically defined in the claims at the end of this specification.

Referring to the drawings for a full and clear understanding of the invention, such as will 35 enable others skilled in the art where such tools are used to construct and use the same, Figure 1 illustrates, in part side elevational 40 part longitudinal sectional view, one form of the novel tool for bushing the ends of metallic tubes, said tool being shown in position in the end of a flexible metallic tube and with a bushing in place to be secured thereto. Fig. 2 is a view similar to Fig. 1, illustrating 45 a preferred modified form of the tool and its application. Fig. 3 is an end view of Fig. 2 as seen looking thereat from the left toward the right hand side of the drawings, the flexible tube and bushing, however, being removed.

In all the figures of the drawings like letters 50 represent like or equivalent parts.

In Fig. 1, D is the body part of the tool, consisting of a metal rod cone-shaped or tapered,

as shown at E, and having at one end an operating-handle H and at the other a cap J. This tapered part E is adapted to slide longitudinally through a tube having a collar M, the body part of said tube being slotted and the free ends F' F² F³ F⁴ turned outward, so as to constitute when held closely together an end flange adapted to be forced against the end of the bushing, so as to effectually secure it to the end of the tube. A B represents a short section of flexible metallic tubing like that disclosed in United States Patent No. 630,501, granted to me on the 8th day of August, 1899. C represents a soft-metal bushing, such as lead or type-metal, approximating in exterior diameter the inner diameter of the tube A B, and I is an end flange adapted to rest, when in position, against the end of the tube to be bushed. This bushing is slipped over the end of the tool and then inserted in place within the end of the tube to be bushed, after which, by rotating and simultaneously forcing the tool toward the end of the tube, the bushing is secured to the inner end thereof.

In the preferred modified form illustrated in Figs. 2 and 3 the collar M is interiorly screw-threaded, and the corresponding end of the body part D has a male screw-thread S, the arrangement being such that when the bushing-ring C is in place and the body part rotated by the handle H the tapered part E will spread the outwardly-turned ends F' F² F³ F⁴, the tool being held by the operator from rotating by lugs L L. After the bushing is thus forced in place the tool is removed by reversing the action of the screw.

I do not limit myself to the specific structures herein shown and described for bushing the interior and ends of metal or other tubes having jagged or cutting projections, such as usually result from the sawing of metal tubes or pipes, as I believe I am entitled to claim, broadly, an expansible bushing-tool adapted to operate in substantially the manner described, so as to expand a yielding expansible metallic bushing against the inner wall of such a tube or pipe, and also in such manner as to force the end flange of the bushing against the end face thereof, so as to form a protecting-bushing.

Having thus described my invention, what

I claim, and desire to secure by Letters Patent of the United States, is—

1. As an article of manufacture an expandible bushing-tool for inserting bushings in the 5 ends of tubes consisting of a slitted tube and a cone-shaped expander, the free ends of the slitted tube being bent outward so as to constitute a sealing-flange for securing the bushing against the end of the tube, said parts being held together at their inner ends and adapted to slide the one through the other.

2. As an article of manufacture a bushing-tool consisting of a slitted tube interiorly screw-threaded, a cone-shaped expander having a corresponding male screw-thread and an 15 operating-handle, the slitted tube being pro-

vided with lugs or arms for holding the tool from turning.

3. As an article of manufacture a bushing-tool consisting of a slitted tube having a screw-threaded collar M and outwardly-turned ends F' F² F³ with holding-lugs L L, in combination with a cone-shaped body part screw-threaded at one end and having an operating-handle H at the other, substantially as described and shown. 20 25

In testimony whereof I have hereunto subscribed my name this 23d day of August, 1899.

EDWIN T. GREENFIELD.
